LIGHT FIXTURE

Max Kushner, Brooklyn, N. Y.

Application December 15, 1949, Serial No. 6,638

Term of patent 14 years

(Cl. D48—4)

To all whom it may concern:

Be it known that I, Max Kushner, a citizen of the United States, residing at Brooklyn, New York, in the county of Kings, and State of New York, have invented a new, original, and ornamental Design for a Light Fixture, of which the following is a specification, reference being had to the accompanying drawing, forming part hereof.

In the drawing:

Fig. 1 is a front elevational view of a light fixture, showing my new design;

Fig. 2 is a side elevational view;

Fig. 3 is a top plan view;

Fig. 4 is a rear elevational view of the same; and Fig. 5 is a horizontal sectional view taken on the line 5—5 of Fig. 4.

Both side views, and the top and bottom views of the light fixture are similar, respectively.

I claim:

The ornamental design for a light fixture, as shown and described.

MAX KUSHNER.
